UNITED STATES PATENT OFFICE.

CLYDE J. COLEMAN, OF NEW YORK, N. Y., ASSIGNOR TO THE HALL SIGNAL COMPANY, A CORPORATION OF MAINE.

ELECTRIC-CIRCUIT CONTROLLER.

SPECIFICATION forming part of Letters Patent No. 693,110, dated February 11, 1902.

Application filed November 24, 1900. Serial No. 37,564. (No model.)

To all whom it may concern:

Be it known that I, CLYDE J. COLEMAN, a citizen of the United States, and a resident of the city, county, and State of New York, have 5 invented certain new and useful Improvements in Electric-Circuit Controllers, of which the following is a specification.

This invention relates to electric-circuit controllers, and more particularly to the character and arrangement of the contacts of such circuit-controllers.

The main purpose of the invention is to provide a pair of contacts which will insure efficient electrical connection when the contacts 15 are brought together and which when lightning traverses the contacts will not be subject to fusion.

The invention is especially useful in relays connected with exposed line-wires, and more 20 particularly where such line-wires form part of electric signaling systems. In electric signaling systems the approved practice requires the contacts in a signal-circuit to be so arranged that when the contacts are opened the 25 signal will go to "danger" and when they are closed the signal may go to "safety," the purpose being to require the signal to be at "danger" in case of a break in a signal-circuit, failure of battery, or other defect. The 30 contact-points in a signal-circuit, however, are subject to fusion by lightning. Hence when the contacts are thus fused a signal is frequently caused to be at "safety" when it should be at "danger." This defect in contacts of signal-circuits has become one of 35 great importance. Contacts which are subject to fusion, as described, may readily more than offset all of the other advantages and safeguards of a signaling system.

40 In the accompanying drawings, forming part of this specification, and in which like reference-numerals designate corresponding parts, Figure 1 is a central vertical section of the relay embodying the invention. Fig. 2 is 45 a front elevation of the relay shown in Fig. 1 with parts broken away. Fig. 3 is a sectional plan view illustrating the contacts shown in Figs. 1 and 2. Fig. 4 is a diagrammatic view of a signaling system to which the 50 invention is applied.

Referring now more particularly to the

drawings, the relay is provided with an insulating block or body 1, to which are fixed the usual binding-posts and on which are supported the magnets 2, provided with the armature-bar 3 for operating one of the contacts. A liquid vessel 4 is supported by a bracket 5 from a base 1. This vessel preferably consists of an insulating body or portion 6, made, for example, of glass or porcelain, and an insulating cap or top 7, made of vulcanite, hard wood, glass, porcelain, or some other suitable material. The body portion 6 is preferably made so as to be readily attached to or detached from the cap, so as to give access to the contacts, which are normally within the vessel. The drawings show for this purpose a threaded flange 8, secured to the under side of the cap 7, into which the body portion 6 may be screwed. Within this passage 4 are supported the contacts, which are opened and closed by the magnets 2. One of these contacts consists of a cup 9, containing mercury, and the other corresponding contact consists of one or more immersion-points 10. These 75 contacts are connected in the circuit which it is desired to open and close, so that when the immersion-point is immersed in the mercury the circuit is closed and when it is withdrawn from the mercury the circuit is 80 broken. These contacts may be brought together and separated by moving either one or the other, or both; but preferably the mercury-cup is stationary and the immersion-point is made movable. In the best form 85 of the invention a bracket 11 is secured to the under side of the cap 7 and supports the mercury-cup 9 at its lower end. The vessel 6 contains a suitable liquid 12, such as naphtha or alcohol, which envelops the pair 90 of contacts and keeps them bright and clean and prevents them from oxidizing. The vessel 4 is provided with a vent-orifice to enable gas or vapor arising from the liquid 12 to escape from the containing vessel, and this 95 vent-orifice is provided with a liquid seal, to be presently described. By this arrangement if lightning traverses the contacts their fusion cannot take place, and hence these contacts may separate and open the 100 circuit in which they are included at the time required. The heat evolved from such pas-

sage of the lightning would be largely absorbed and dissipated by the liquid 12, and any mercury which might be vaporized by the passage of the lightning would be condensed by the liquid and fall to the bottom of the vessel 4. The accumulation of gas or vapors generated by the heating of the liquid 12 would pass off through the vent-orifice in the vessel 4. In the present embodiment of the invention, as shown in Figs. 1, 2, and 3, a bracket 13, similar to and insulated from the bracket 11, carries the mercury-cup 14, and the circuit, which is connected with the brackets on the outside of the cap 7, is closed by bridging the cups 9 and 14. Mercury-cups 15 and 16, which are supported by brackets 17 and 18, are connected in another circuit, which is closed by bridging the mercury-cups 15 and 16. A bracket 19 carries an arm 20, pivotally mounted thereon, which is provided at its outer ends with bridging-pieces 21 and 22, the ends of which carry immersion-points, such as immersion-points 10, adapted to be immersed in and withdrawn from the mercury-cups for the purpose of closing and opening the circuits. When one end of the arm 20 is depressed, the mercury-cups 9 and 14 are electrically connected through the bridge-piece 21, and when the other end of the arm 20 is depressed the circuit through the mercury-cups 9 and 14 is broken, and the circuit through the mercury-cups 15 and 16 is closed through the bridge-piece 22. In arranging the vent-orifice for the vessel 4 I preferably provide an annular cup 23, secured to and extending above the cap 7, and a cap 24, whose side wall extends into the cup 23 intermediate to its side walls. The cup 23 is made to contain a suitable sealing liquid, preferably mercury, which fills the space between the inner and outer side walls of the cup 23 and on both sides of the cap 24, thus forming an inner column and an outer column. The cap 24 is closed at its top and open, of course, at its bottom, as shown. I preferably arrange the cap 24 and cup 23 so that the inner column will be thinner than the outer column. I also preferably provide the outer wall of the cup 23 with an enlargement 25 and the inner wall with a contracted portion 26, so as to provide enlarged spaces at the tops of these walls to prevent the overflow of the sealing liquid. Connected to the arm or lever 20 is a connection or rod 27 for actuating the movable contacts. In the form of the device shown in the drawings this connection 27 passes through the bore 28 of the seal 23 and is secured to the cap 24. The armature-bar 3 engages under an adjustable nut 29 on a rod 30, projecting from the top of the cap 24, so that the movement of the armature-bar 3 opens and closes the contacts. The vapor which rises from the liquid 12 in the vessel 4 rises under the cap 24 and tends to depress the inner annular column of the sealing liquid below the bottom of the cap 24, so as to

permit the accumulated vapor to escape, and thus this vapor is enabled to escape to the outside air by passing up through the outer column of the sealing liquid when the pressure of the vapor has reached a certain point in the vessel 4. Thus the sealing liquid prevents the accumulation of undue pressure of vapor and at the same time prevents the entrance of air into the vessel 4, which might occasion an explosive mixture, and the sealing liquid also prevents the entrance of dust or other foreign matter into the vessel 4.

Various embodiments of the several features of the invention may be employed without departing from the scope of the invention. For example, the purpose and advantage of the liquid 12, which envelopes the contacts, may be attained, at least in part, if this liquid only covers the contacts at the time they separate. The immersed points, for example, after separating from the mercury might move entirely above the surface of the enveloping liquid. It would be better, of course, to have the contacts permanently and entirely immersed in the enveloping liquid. Moreover, while I prefer for the sake of compactness and convenience, as well as economy, and for other reasons to employ the liquid-sealed vent-orifice to provide a passage for a connection from outside the vessel 4 with the moving contact inside said vessel, the invention is not limited to such an arrangement. This connection may extend from the contact inside the cup to the outside of the cup through some other appropriate opening. Again, any means may be employed for actuating the movable contact, such as electric, pneumatic, mechanical, or other means. Furthermore, it is not even essential that the movable contact within the vessel have a mechanical connection with the outside of said vessel, since a magnet on the outside of the vessel may be employed to move said contact by the force of magnetic attraction operating through the wall of the vessel.

In the diagram shown in Fig. 4 a relay embodying the invention already described is connected up with signal-circuits for signals which stand normally at "danger." In said diagram, 31, 32, and 33 represent three blocks of a track. Blocks 32 and 33 are guarded by the signals 34 and 35, respectively. The rails of the block 32 are connected in a normally closed circuit, which includes the magnets 2, operating the armature-bar 3, which is in operative connection with the lever 20, carrying immersion-points at one end to bridge the mercury-cups 9 and 14 and carrying at its other end immersed points to bridge the mercury-cups 17 and 18. The circuit of the signal 35 is normally open at the mercury-cups 9 and 14. The rails of the block 31 are connected up with another magnet 2, having its contacts arranged in the same way as that just described. The circuit of the signal 34 is normally open at its mercury-cups 9 and 14 and is normally closed at the mercury-

cup 17 and 18. A train on the block 31 moving in the direction of the arrow shunts the magnet 2 in the usual manner, thereby putting to "danger" the signal behind the train, closing at 9 and 14 the circuit of the signal 34, and putting the signal to "safety" in advance of the train. When the train enters block 32, the signal 34 goes to "danger," since its circuit will be broken at 17 and 18. The signal 35 goes to "safety," since its circuit will be closed at 9 and 14. If the contacts at 17 and 18 in the circuit of the signal 34 were ordinary metallic contacts, lightning striking the signal-circuit would be apt to fuse the contacts, so that a train entering block 31 might put the signal 34 to "safety," although another train was in block 32. If, however, my circuit-controller, which has been already described, is employed, as indicated in Fig. 4, lightning would be unable to fuse the contacts at 17 and 18 in the circuit of the signal 34, so that the effects of lightning would not enable the signal 34 to go to "safety" when it ought to be at "danger."

It will be understood that the circuit-controller which is the subject of this invention not only prevents the fusion of contacts due to lightning, but it also prevents sparking of the contacts with its attended evils.

What I claim as new, and desire to secure by Letters Patent, is—

1. A circuit-controller including in combination a cup designed to hold a body of mercury as one contact; an immersion-point as the other contact, said contacts being so arranged that they may be brought together and separated to close and open the circuit; and a closed vessel designed to contain a suitable liquid to envelop said contacts and having a liquid-sealed vent-orifice.

2. A circuit-controller including in combination a cup containing a body of mercury as one contact; an immersion-point as the other contact, said contacts being so arranged that they may be brought together and separated to close and open the circuit; and a closed vessel containing a suitable liquid to envelop said contacts and having a liquid-sealed vent-orifice.

3. A circuit-controller including in combination a cup designed to hold a body of mercury as one contact; an immersion-point as the other contact, said contacts being so arranged that they may be brought together and separated to close and open the circuit; and a closed vessel designed to contain a suitable liquid to envelop said contacts and having a mercury-sealed vent-orifice.

4. A circuit-controller including in combination a cup designed to hold a body of mercury as one contact; an immersion-point as the other contact, said contacts being so arranged that they may be brought together and separated to close and open the circuit; and a closed vessel designed to contain a suitable liquid to envelop said contacts and having a mercury-sealed vent-orifice leading from

the interior of said vessel above the liquid therein.

5. A circuit-controller including in combination a cup designed to hold a body of mercury as one contact; an immersion-point as the other contact, means for bringing together and separating said contacts to close and open the circuit; and a closed vessel designed to contain a suitable liquid to envelop said contacts and having a liquid-sealed vent-orifice.

6. A circuit-controller including in combination a cup designed to hold a body of mercury as one contact; an immersion-point as the other contact; a closed vessel designed to contain a suitable liquid to envelop said contacts and having a liquid-sealed vent-orifice; one of said contacts being stationary and the other movable within said vessel so that said contacts may be brought together and separated to close and open the circuit, said movable contact having an actuating connection extending outside the liquid vessel through its vent-orifice.

7. A circuit-controller including in combination a vessel designed to contain a suitable liquid and comprising an insulating-cap and a readily-detachable body portion, said cap having a liquid-sealed vent-orifice; a cup designed to hold a body of mercury as one contact and supported by said cap within the body of said vessel; an immersion-point within said vessel and constituting the other contact and arranged to move into and out of contact with the mercury to close and open the circuit, said immersion-point having a connection extending through the vent-orifice of said cap; said contacts being arranged and designed to be enveloped by the liquid in said vessel.

8. A circuit-controller including in combination a vessel containing a suitable liquid and having a vent-orifice in its top; a liquid seal for said orifice comprising an annular cup containing a sealing liquid and a vertically-movable cap having its side wall immersed in the sealing liquid of the cup intermediate the side walls thereof; a cup containing mercury as one contact and supported within the vessel from the top thereof; an immersion-point movable into and out of the mercury to close and open the circuit; and an actuating connection for the immersion-point extending from within the vessel out through the vent-orifice and liquid seal, the contacts being immersed in the liquid contained in said vessel.

9. In a signaling system for railways, the combination of a signal; a signal-circuit therefore containing a pair of contacts, the arrangement being such that when the contacts are open the signal will go to danger and when they are closed the signal may go to safety, said contacts including a body of mercury and an immersion-point, whereby in case of lightning on the signal-circuit, fusion of the

contacts will be prevented and the signal will be thus enabled to go to danger at the proper time, a closed vessel having a liquid-sealed vent-orifice and containing a suitable liquid 5 in which the contacts are immersed.

10. A circuit-controller including in combination a vessel designed to hold a body of mercury as one contact, an immersion-point as the other contact, means for bringing the 10 contacts together and for separating them to close and open the circuit, and a vessel for

holding the said contact-points designed to contain a suitable liquid to envelop said contacts.

In testimony whereof I have signed my 15 name to this specification in the presence of two subscribing witnesses.

CLYDE J. COLEMAN.
